UNITED STATES PATENT OFFICE.

ALFRED E. GRAVES, OF BOSTON, MASSACHUSETTS, ASSIGNOR TO PACKAGE CONFEDERATION COMPANY, A CORPORATION OF MASSACHUSETTS.

WRAPPING-MACHINE.

1,101,125.

Specification of Letters Patent. Patented June 23, 1914.

Application filed August 2, 1913. Serial No. 782,633.

To all whom it may concern:

Be it known that I, ALFRED E. GRAVES, of Boston, in the county of Suffolk and State of Massachusetts, have invented certain new and useful Improvements in Wrapping-Machines, of which the following is a specification, reference being had to the accompanying drawings, forming part thereof.

This invention has reference to improvements in wrapping machines and particularly to such machines adapted to receive a wrapper and a roll of candy wafers or lozenges, to apply said wrapper to said roll and to turn the ends of said wrapper against the ends of said roll or against the articles forming the ends of said roll.

One object of this invention is so to construct a wrapping machine of the nature herein described that one edge of the wrapper may be tucked beneath an overlapping edge thereof and said latter edge be smoothed into position.

Another object of this invention is so to construct a wrapping machine for a roll or stack of flat articles that the constituent elements of said roll or stack may be held together in alinement during the application of the wrapper to the periphery of the roll or stack and, preferably, until portions of the ends of the wrapper are turned in against the ends of said stack or roll.

Other objects of the invention will appear from the following description.

The invention consists in the novel construction of the carrier frame and roll carrying devices mounted thereon.

The invention also consists in the novel means for applying the wrapper around the roll.

The invention also consists in the means for holding the wafers or lozenges in alinement.

The invention still further consists in such other novel features of construction and combination of parts as shall hereinafter be more fully described and pointed out in the claims.

Figure 1, represents a front elevation of the improved wrapping machine partially broken away and partially in section as taken on line 1—1 Fig. 3. Fig. 2, represents an end view of the machine looking at it from the right hand end in Fig. 1, parts be-

ing broken away. Fig. 3, represents a vertical sectional view of parts of the machine taken on line 3—3 Fig. 1. Fig. 4, represents a front view of portions of the machine showing details of the tucking mechanism. Fig. 5, represents a sectional view of parts of the same taken on line 5—5 Fig. 2. Figs. 6, 7, 8, and 9 are diagrammatic views illustrating the turning in of the ends of the wrapper.

Similar characters of reference designate corresponding parts throughout.

In carrying this invention into practice I construct a machine having the end frames 11 and 12 connected by the tie rods 13, 13 and 14, 14 and provided with the table top 15 having the slot or opening 16 of a size 70 and shape adapted to permit the passage therethrough of the roll A and its wrapper B, indicated in Fig. 3 of the drawings.

Rotatably mounted in the frames 11 and 12 is the sleeve 17 on which is mounted and secured the carrier comprising the frame members 18 and 18 substantially of the shape shown in Fig. 3 and having the radial arms 19, 19 to which are secured plates 20, 20 arranged in pairs connected by troughs 21 and having the guide slots 22, 22 in which are slidable the shafts 23, 23 having at their outer ends, outside said carrier frames 18, 18 followers 24, 24 and the tucker plates 25, 25 the longitudinal slots of which are engaged with the guide pins 26, 26 of said plates 21, 21.

Slidable transversely in each pair of said plates 21, 21 are the rack rods 27, and 28 having respectively the pressers 29 and 30, provision being made by the pinion 31, in engagement with the racks of said rods 27, 28 to transmit motion from one of said rods to the other, and rod 27 being provided with the spring 32 acting to move said rod in one direction. Journaled in each pair of said plates 21, 21 are pairs of shafts 33, 33 and 34, 34. On shafts 33, 33 at the inner sides of plates 21, 21 are mounted the arms 35, 35 connected in pairs by the curved pressure plates 36, 36 while the outer ends of said shafts 33, 33 are furnished with the arms 37, 37 having the followers 38, 38. On shafts 34, 34 are mounted the tucker arms 39, 39 having at their ends the tucker plates 40, 40 while on the outer ends of these shafts

34, 34 are mounted the arms 41, 41 having the followers 42, 42.

Mounted on the inner side of frame member 12 is the fixed cam 43 adapted during 5 part of the rotation of the carrier to bear against the end of rack rod 27 until the package or roll reaches the devices for turning in the first folds in the ends of the wrapper approximately at which time the 10 followers 42, 42 of arms 41, 41 are engaged and actuated by the cam 44, also fixed to said frame member 12, while to both of said frame members 11 and 12 are fixed the projector cams 45, 45 and the retractor cams 46, 15 46 adapted to engage and actuate the followers 24, 24 of shafts 23, 23.

Mounted on the frames 11 and 12 are yielding bearings carrying the pressure rolls 47, 47 which rolls are positioned to act 20 against one end of the wrapper B during the passage of said rolls of the package A moving with the carrier.

The first folder or tucker devices 48, 48 are mounted on the rock shaft 49 which is 25 mounted in the bearing brackets 50, 50 of said frames 11 and 12 and has, outside frame 12, the lever arm 51 connected by the pivoted link 52 with the spring retracted lever 53 mounted to swing on said stud extending 30 from said frame 12.

Frame member 12 has the slots 12', 12', through which extend pins 54, 54 carrying at their inner ends the cam member 55 having the internal cam 56 and the external cam 35 57 which during the partial rotation of this cam member 55 acts against the followers 38, 38 of the arms 37, 37 to rock their shafts and to swing their pressure plates 36, 36 toward each other. The partial rotation of 40 cam member 55 is effected through the ring 58 in which the outer ends of pins 54, 54 are secured and having the studs 59 and 60, this ring 58 is journaled on the sleeve of locking disk 61 which is keyed to sleeve 17 and has 45 radially extending notches 62, 62, Figs. 2 and 5, adapted to be engaged by the bolt or latch 63 slidable in guides at the outer side of frame 12 and operated by the bell crank lever 64, 65 connected with said latch 63 50 and pivotally mounted on a stud extending from frame member 12; spring 66 being provided to act on said bell crank lever in the direction of engagement of latch 63.

Journalized in the bore of sleeve 17 is shaft 55 67 having at its ends the tucker arms 68, 69 one of which has a limited movement between the stops 70 and 71 of frame member 12, and extending between these arms 68, 69 is the tucker blade 72 which is actuated in 60 the direction in which the package under operation moves by said arms 68, 69. Pivotally mounted on the tucker arm 68 is the pawl 73 having the lever arm 74 which is adapted to be engaged, during the final por-

tion of the forward movement of arm 68, by pin 75 of frame member 12 at this time to disengage pawl 73 from the ratchet disk 76 rotatable on said shaft 67 and having the pin 77 by which said disk 76 is connected with the arm 78 which latter is journaled on the sleeve 17 between disk 61 and tucker arm 68. Pivotally mounted on arm 78 is pawl 79 having the member 80, said pawl 79 being adapted, when moved forward to engage in one of the notches or sockets 82 of the disk 61 to effect the intermittent rotation of said disk. As the first movement of arm 78, from the position shown in Fig. 2, is downward said arm 78 strikes pin 60 of ring 58 and effects the swinging of said ring and 80 cam member 55, attached thereto, to bring its cams 56 and 57 between the followers 38, 38 of arms 37, 37 and to cause the swinging of said arms and the rocking of their shafts whereby the presser arms 35, 35 and their plates 36, 36 are moved toward each other. At a point in the forward, driving movement of arm 78 member 80 of its pawl 79 strikes stud 59 of ring 58 and shifts said ring so that cam member 55 is shifted to 90 move its cams 56, 57 from between the followers 38, 38 to permit the separating movement of plates 36, 36.

At the upper portion of frame 12 in alignment with rack rod 27 of the closing device 95 positioned to receive a roll and its wrapper is the guide 82 having the slide 83 furnished at its inner end with the head 84 and actuated by the arm 85 of the bell crank having the shaft 86 journaled in bearings mounted on frame 12 and having the arm 87 provided with the operating rod 88 having the followers 89 and slidably engaged with the stud 90 of frame 12 on which stud is journaled the gear 91 having the cams 92 and 93 of which cam 92 is adapted to act at each rotation of gear 91 against followers 89 of rod 88 to effect the lifting of said rod and, through its connections therewith, the actuation of the slide rod 83, while cam 93 acts against the lower end of pivoted arm 52 to cause the swinging of said arm to swing the first folders 48, 48 over the ends of a package positioned relative thereto. When rack rod 27 is pushed inward by the head 84 of the slide 100 rod 83 said rack rod is adapted to be held inward by cam 43 of frame 12 during the rotation of package carrier from the receiving position approximately to the first folding position.

Gear 91 is driven by gear 94 journaled on a stud extending from frame 12 and having cam 95, to act against lever arm 65 and effect the releasing movement of latch 63 from latch disk 61, and stud 96 which is connected by the pivoted rod 97 with a similar stud on the pawl arm 78, these members being so timed as to their operation that latch 63 is 110 120 125

released from disk 60 before stud 96 reaches a position to act, through rod 97, to swing pawl arm upward and to effect the intermittent rotation of latch disk 61 and sleeve 17, to which said disk is keyed, with the carrier frames 18, 18 mounted on said sleeve.

Gear 94 is driven by pinion 98 mounted on shaft 99 which is journaled in bearings and is driven in a suitable manner, the proportions of said gear 94 and pinion 98 being such that pinion 98 rotates more rapidly than gear 94 and preferably makes two or more rotations for each rotation of gear 94.

With one of the receptacles or troughs 21 and its related mechanism in position beneath the slot or opening 16 of table 15, a wrapper B is placed on said table over said opening and a stack or roll A of wafers or lozenges is placed on said wrapper and pressed downward with the said wrapper through the said opening to the position indicated in dotted lines in Fig. 3. This placing of the roll A and its wrapper B in the receptacle 21 is timed with relation to the operation of the machine which now acts by means of cam 92 on the followers 89 of the rod 88 to swing the bell crank having arms 87, 85 to move slide rod 83 inward whereby the head 84 of said rod pushes rack rod 27 and said motion is transmitted by pinion 31 to rack rod 28 so that the pressers or heads 29 and 30 respectively of said rods are brought to bear against the ends of the stack of wafers or the articles to hold said wafers or articles together in stack form. At or about this time cam 95 of gear 94 acts against lever 65 to effect its release of latch 63 from the notch or latch disk 61 whereby said disk is free to rotate. The rotation of gear 94 in the direction indicated by its arrow effects, through rod 97, first a retractive movement of pawl arm 78 until said arm engages pin 60 of ring 58 and causes the shifting of said ring whereby the cam member 55, connected with ring 58 by pins 54, 54, is also shifted to bring its cams 56 and 57 to act against followers 38, 38 thus moving said followers to cause the rocking of the shafts 33, 33 and the swinging of the arms 35, 35 to bring their presser plates 36, 36 against the wrapper as indicated in Fig. 6. As, under the continued rotation of gear 94, pawl arm 78 is moved upward said arm through its pin 77 effects the rotative movement of ratchet disk 76 and such movement is transmitted by pawl 73 to its tucker arm 68 whereby both of said tucker arms are swung and tucker 72 is advanced to tuck down the rear end of the wrapper B, as indicated in Fig. 7, and as this application is accomplished cam member 74 rides on to pin 75 whereby pawl 73 is disengaged from ratchet disk 76 and the tucker arms 68, 68 are free to move back-

ward under the retraction of their spring. 65 At or about the accomplishment of this tucking operation pawl 79 of arm 78 engages one of the notches 62 in latch plate 61 and effects the rotative movement of said plate and the sleeve 17 with the parts attached thereto. In such movement the end of rod 27 moves off of pusher head 84 and is engaged by cam 43 which prevents its outward movement of said rod 27, the roll A and its wrapper is carried beneath rolls 47, 47 which roll down the final edge of the wrapper and as the rod 27 moves by the end portion of cam 43 the spring of said rod 27 causes it to move outward and said motion of this rod is transmitted by pinion 31 80 to rod 28 whereby the pressers 29 and 30 are moved out of the way to permit at this time, the infolding of end portions of the wrapper, see Fig. 8, by the first folders 48, 48 the followers 42, 42 of the side folders or 85 second and third folders 40, 40 are engaged and actuated by cam 44 whereby said folders 40, 40 are swung to the position shown in Fig. 9 to fold inward portions of the wrapper and subsequently the followers 24, 24 of shaft 23 ride over the projector cams 45, 45 and effect the projection of the fourth folder plates 25, 25 to the position indicated in dotted lines at the left hand side of Fig. 8 making the final folds in the ends 90 of the wrapper. Thereafter cams 46, 46 act against said followers 24, 24 to retract shaft 23 and its folder blades 25, 25 while pawl arm 78 moves to a position to engage member 80 of its pawl 79 with stud 59 of 100 ring 58 whereby said ring and cam member 55, connected therewith are shifted to release cams 56 and 57 from the followers 38, 38 of the presser plates 36, 36 so that said pressers may separate to permit the discharge of the wrapped roll or package. As each of the notches 62 of the plate 61 is brought into registry with latch 63 said latch engages therewith and locks the package carrier mechanism against rotation. 110

Having thus described my invention I claim as new and desire to secure by Letters Patent—

1. A wrapping machine of the nature described, comprising a table having a slot 115 through which a package with an open wrapper may pass, a rotary carrier having a package receptacle adapted to be positioned beneath said slot, means for intermittently actuating said carrier and having 120 a ratchet, tucker arms mounted to swing about the axis of said carrier and having a tucker blade extending the length of said package receptacle, a pawl pivotally mounted on one of said tucker arms and adapted to engage said ratchet, and coöoperating means for disengaging said pawl from said ratchet during the movement of said carrier. 125

2. A wrapping machine of the nature described, comprising a rotary carrier having a receptacle adapted to receive a package with a wrapper open at the ends of said package, and means mounted on said carrier and adapted to be entered in the open ends of said wrapper to bear against the open ends of the package therein. 65

3. A wrapping machine of the nature described, comprising organized means for receiving a package of articles with a wrapper open at its ends and for carrying said package to end folding devices, movable means for sustaining said articles in said wrapper, wrapper end folding devices, and means for retracting said sustaining means prior to the operation of said end folding devices. 70

4. A wrapping machine comprising a rotary carrier having a receptacle adapted to receive a package with a wrapper open at its ends, end sustaining means for the articles of said package slidably mounted in said carrier, and actuating means for said sustaining means, said actuating means located at the package receiving position. 75

5. A wrapping machine comprising a frame, a package carrier mounted to rotate in said frame and having a series of receptacles to receive packages with wrappers open at their ends, a pair of rods slidable in said frame adjacent each of said receptacles and having means adapted to enter the ends of said wrapper, means for transmitting motion from one of said rods to the other, and means for preventing the sliding of one of said rods during the rotation of said carrier, means for intermittently rotating said carrier, and means actuated by such carrier 80 rotating means for sliding one of said rods to position to be engaged by said cam. 85

6. A wrapping machine of the nature described, comprising a frame having a cam and a slidable actuator located adjacent said cam, a carrier rotatable in said frame and having a receptacle to receive a package with its wrapper open at its ends, a pair of rack rods slidable in said carrier and having pressers adapted to enter the ends of said wrapper, a pinion engaged with the racks of said rods, means for intermittently rotating said carrier, and means for operating said actuator at times. 90

7. A wrapping machine of the nature described, comprising a rotary carrier having a receptacle to receive a package and its wrapper open at the ends and at its lapping edges retractable means to enter said open ends to sustain the articles of said package, means to press the wrapper around said package, means for tucking in one edge of said wrapper, means for turning down the other edge of said wrapper, a series of wrapper end folding devices, and mecha- 95

nism for operating said carrier and said end turning means intermittently. 100

8. A wrapping machine of the nature described, comprising a frame having a shaft, a carrier rotatable about said shaft, and having a receptacle to receive a package with an open wrapper, arms mounted on said carrier to swing and having pressers to partially close said wrapper, means for actuating said arms including levers having followers, a cam rotatively shiftable around said shaft and adapted to act on said followers, and means operating in one direction to effect the intermittent rotation of said carrier in the other direction to effect the shifting of said cam. 105

9. A wrapping machine of the nature described, comprising a rotary carrier having means to receive a package with an open wrapper, shafts journaled in said carrier, arms mounted on said shafts and having presser plates, follower arms on said shafts, an annular rotatably shiftable way on which said followers are adapted to travel and having cams to actuate said followers, means to effect intermittent rotation of said carrier, and means actuated by a movement of carrier actuating mechanism for shifting said way intermittently to engage and release said followers. 110

10. A wrapping machine of the nature described, comprising a rotary carrier having a receptacle to receive a package with an open wrapper, means on said carrier to sustain the articles within said wrapper, means on said carrier for pressing the wrapper around the package, end folding devices operatively mounted on said carrier, a frame in which said carrier is mounted, cams on said frame for actuating said pressing means and said folding devices, and means for effecting the intermittent rotation of said carrier. 115

11. A wrapping machine of the nature described, comprising a frame, a presser roll thereon, a folder shaft journaled in bearings of said frame and having a pair of folder plates and a crank arm, a carrier rotatively mounted in said frame and having a receptacle to receive a package, wrapper pressing means, wrapper end folding means both carried by said carrier, means on said frame for actuating said pressing and folding means, a tucker having arms mounted to swing about the axis of said carrier, means for intermittently rotating said carrier, and a connection between said tucker arm and said carrier, and rotating means to operate the tucker arm positively in one direction. 120

12. A wrapping machine of the nature described, comprising a frame, a sleeve journaled in said frame and having a carrier, package receptacles on said carrier, wrapper pressing devices, related to each of the 125

said receptacles, a shaft journaled in said sleeve and having a pair of arms furnished with a tucker, a pawl on one of said tucker arms, a ratchet on said shaft adapted to be engaged by said pawl, and a pawl and ratchet connection for actuating said sleeve and its carrier, said last mentioned pawl mecha-

nism having an arm positively connected with said first mentioned ratchet.
